CLAIM

The ornamental design for a beverage helmet, as shown and described.

DESCRIPTION

FIG. 1 is a front perspective view of an embodiment of the beverage helmet;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines and unshaded areas within the broken lines define portions of the beverage helmet that form no part of the claimed design.
